VERY HIGH FREQUENCY ELECTRIC DISCHARGE DEVICE

Gesinus Diemer, Eindhoven, Netherlands, assignor to Hartford National Bank and Trust Company, Hartford, Conn., as trustee

Application November 19, 1952, Serial No. 321,469

Claims priority, application Netherlands December 6, 1951

2 Claims. (Cl. 315—4)

The invention relates to devices of the kind comprising an electric discharge tube which is suitable for use at very high frequencies and, more particularly, to devices and tubes operating on the dynatron principle, in which the tubes are connected to concentric Lecher systems. For very high frequencies (250 to 1000 mc./s.) use is frequently made of tubes of special construction, for example, tubes comprising sealed-in discs. These constructions, however, differ considerably from those of conventional tubes.

According to the invention it is now possible to manufacture tubes, in principle, of the conventional construction, particularly suitable for connection to concentric Lecher systems and operating satisfactorily up to 1000 mc./s. According to the invention this may be obtained, if with a device comprising an electric discharge tube for very high frequencies, having an electrode system including an electron gun which produces a ribbon-shaped beam directed to a secondarily emissive auxiliary cathode, the secondary electrons of which are collected by an anode, the auxiliary cathode has a U-shaped cross-sectional area, the closed side of which faces the electron gun, the auxiliary cathode being supported by a central pin, which is secured between the limbs of the U and is taken directly through the bottom of the tube to the outside, the cylindrical anode surrounding coaxially the auxiliary cathode and being secured to a plurality of studs sealed in a circle around about the central pin of the auxiliary cathode, to which studs are also secured inside and outside the tube cylindrical screens forming a prolongation of the anode to a concentric Lecher system, the central conductor of which is in line with the central pin of the auxiliary cathode.

This arrangement may provide the same advantages as tubes having sealed-in discs, without the need of sealing such large disc-shaped members in glass, since the tube construction according to the invention may, in principle, be identical with the conventional construction of tubes having a glass bottom, more particularly, of small tubes, for example, having a bulb diameter of less than 25 mms.

Owing to the central arrangement of the pin of the auxiliary cathode, which is coaxially surrounded by a screen of the anode, also outside the tube, a concentric Lecher system can be secured to the pin and the screen in a very simple manner. Moreover, parasitic radiation is avoided, since the auxiliary cathode itself is also completely surrounded by the anode, so that no radiation damping occurs and a high alternating voltage is permissible between the anode and the auxiliary cathode. Moreover, all supply pins are located at one end of the tube. Since the screens associated with the anode extend inside and outside the tube as far as the proximity of the tube bottom, substantially the same effect is obtained as with an uninterrupted screen sealed in the bottom of the tube.

In order that the invention may be readily carried into effect, it will now be described in detail with reference to the accompanying drawing, in which

2

Fig. 1 shows a tube for use in the device according to the invention,

Fig. 2 is a cross sectional view of the electrode system of the tube shown in Fig. 1 and

Fig. 3 is a bottom view of the tube bottom.

Referring to Fig. 1, reference numeral 1 designates the bulb of the tube, which may be secured to a concentric Lecher system 2. The tube comprises an electron gun 3, an anode 4 and screens 5 and 6, which constitute a prolongation of the anode 4, whereas the screen 7 is to be regarded as a prolongation of the screen 6 and hence of the anode cylinder outside the tube. The screen 5 is closed at the upper end by a metal plate 8, in which is secured the cesium pill to activate the secondarily emissive auxiliary cathode 9, housed inside the anode 4 (Fig. 2). This auxiliary cathode 9 is formed by a U-shaped strip of copper plated nickel, the limbs of which are soldered to the central pin 10. The limbs also serve as cooling members and the closed side of the U constitutes the auxiliary cathode proper, the convex surface of which, coated with secondarily emissive material is arranged opposite a slit 11 of the anode 4, so that oscillation of the secondary electrons is avoided.

The electron gun 3 may be of conventional construction and comprise, for example, a cathode 12, behind which a screen 13 is provided. The intensity of the flow of electrons is governed by the plates 14 (g₁) whereas the concentrating plates 15 may be connected to the cathode 12. The acceleration electrode 16 (g₂) has a narrow slit 22. In this case the anode 4 is made of copper plated nickel and is welded to two studs, which are taken directly through the tube bottom to the outside. However, as an alternative, a larger number of studs may be arranged in a circle and connected to the anode 4. These studs also support the screens 5, 6 and 7. The anode 4 is arranged between two mica centering members 17 and 18 and is blackened on the outer side to improve thermal irradiation.

Fig. 3 shows the connections of the various inlets to various electrodes.

The mica member 17 has two apertures 19, having a diameter of 3 mms. to allow the cesium vapour to pass; the apertures are indicated by dashes in Fig. 2. Opposite the slit 11 of the anode 4 is provided a narrow slit 20 in the two mica centering members 17 and 18, in order to reduce electrostatic leakage and high-frequency losses.

At the top inside the tube a barium getter holder 21 is secured to the closing plate 8.

In a dynatron circuit-arrangement comprising a tube, the cathode 12 of which has a sprayed surface of 0.75 mm. in width and 10 mms. in length a very favourable effect is obtained. The slit 22 of the accelerating anode 16 is 0.8 mm. The slit 11 has a width which is smaller than the width of the cathode 12 or equal thereto, i. e. 0.7 mm. and the width of the auxiliary cathode 9 facing the slit 11 is 300 μ and the distance between the anode 4 a half times to twice the width of the slit 11, i. e. 1.4 mms. The distance between the auxiliary cathode 9 and the slit 11 is 300 μ and the distance between the anode 4 and the accelerating electrode 16 is 0.5 mm.

It was found that these dimensions of the tube could provide an output of

0.53 watt at 200 mc./s.

0.35 watt at 300 to 500 mc./s.

0.10 watt at 800 mc./s.

A construction according to the invention has an additional, important advantage in that these results were obtained without using exceptionally high voltages, i. e. 250 v. at the anode 4, 100 v. at the accelerating electrode 16 and about 40 v. at the auxiliary cathode 9.

It was found that a negative resistance of 1000 to 2000 ohms could occur between the auxiliary cathode 9 and the anode 4, which is sufficient to excite a good circuit to a frequency of 1000 mc./s.

Although the tube construction diverges, in principle, little from that of conventional small-sized tubes, the same advantages and results are found to be obtainable as those of very special constructions, such as light-house tubes and the like, which, however, must be driven by high voltages (about 1000 v.).

What I claim is:

1. An electric discharge device adapted for operation as a dynatron oscillator at very high frequencies, comprising an envelope including a bottom portion, an electron gun for producing a ribbon-shaped beam disposed in said envelope, a U-shaped auxiliary cathode in said envelope having a secondary-electron-emissive surface on its base facing said electron gun, a pin extending through the bottom portion of said envelope and secured in the envelope between the limbs of the U-shaped cathode for supporting said U-shaped cathode in its operative position, a cylindrical anode having an aperture for passage of the ribbon-shaped beam coaxially surrounding said pin and said U-shaped cathode for collecting the second-

ary electrons produced thereby when bombarded by the ribbon-shaped beam, a plurality of connecting studs arranged coaxially with said pin and extending through the bottom portion of said envelope and secured to and supporting said cylindrical anode, a cylindrical screen external to said envelope surrounding said pin and secured to and supported by said studs, and a Lecher system external to said envelope for transferring energy from said device to an external circuit, said Lecher system including a central conductor aligned with said pin, said Lecher system further including a cylindrical conductor surrounding said central conductor and aligned with said cylindrical screen.

2. An electric discharge device as claimed in claim 1 in which a further cylindrical screen aligned with said cylindrical anode is disposed between said anode and the bottom portion of said envelope, said further screen being secured to and supported by said connecting studs.
